PAINT BRUSH FERRULE

Vincent J. Kersting, Roselle Park, N. J.

Application November 23, 1933, Serial No. 699,444

1 Claim. (Cl. 15—171)

The object of this invention is to provide a novel ferrule for paint brushes and the like, and, specifically, to provide a ferrule the overlapped portions of which are joined together by welding, 5 preferably by spot welding.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in elevation, a paint brush equipped with the ferrule forming the subject matter of this application;

Fig. 2 is a transverse section of the ferrule;

Fig. 3 is a longitudinal section of the ferrule;

Fig. 4 is an elevation of the ferrule.

Fig. 5 is an elevation showing a modified form of the invention, the edges of the ferrule being spaced apart;

Fig. 6 is a transverse section showing the edges 30 of the ferrule of Fig. 5 overlapped.

The numeral 1 marks a handle of a paint brush, the handle generally being made of wood and comprising an enlarged head 2, upon which the body bristles 3 are held by a metal ferrule 4. The 35 ferrule 4 has circumferential, outwardly struck beads 5, and carries an inscription 6, generally of an advertising nature, and therefore represented in the present drawing by the legend "Paint Brush". The ends of the ferrule 4 are overlapped, as shown at 7, and are held together 40 by spot welding, preferably located on the inside of the ferrule, and designated by the reference character 8.

In welding the ferrules, as hereinbefore described, the metal at the joint is rendered as strong as any other part of the ferrule, and the strength at the joint often is greater than elsewhere.

The invention, therefore, places the device in a 50 class with a seamless ferrule, but with an additional advantage which will now be alluded to. The bead lines shown in the drawing serve as a guide for setting the handle and the bristles, but these beads cannot be made in a seamless ferrule.

55 The same observation holds true with respect to

the inscription shown at 6, since this inscription cannot be made in a satisfactory way, commercially, in a seamless ferrule. The bead lines and the lettering form, so far as manufacture and marketing are concerned, an essential part 60 of a paint brush. It can be turned out readily in the device forming the subject matter of this application, but they are practically impossible when a seamless ferrule is provided. The manufacturer of the goods is entitled to the beads, 65 to facilitate the manufacture and assembly of the brush, and the manufacturer or retailer is entitled to the marking indicated generally by the words shown at 6, in order to identify the product. 70

Various expedients have been resorted to in the past, in an effort to turn out a ferrule for paint brushes, the ends of the ferrule being brought together and secured together. Butt ends have been suggested, connected together by 75 solder, or otherwise, but a union which comprises a butt end is unsatisfactory in a paint brush. Soldering processes, furthermore, have not afforded the desired strength, and have proven expensive to manufacture. In the device 80 forming the subject matter of this application, the spot welding shown at 8 may be carried out with great rapidity, thereby cutting down the cost of the article, providing a ferrule which is equal in all respects to a seamless ferrule, and, 85 at the same time, permitting beading and lettering, which is something not possible in a seamless ferrule.

In Figs. 5 and 6, the ferrule 10 has beads 11 as hereinbefore described. One end of the ferrule 10 marked by the numeral 12 is plain whereas the other end of the ferrule, marked by the numeral 14 is provided with a line of bosses 15 struck from the end 14 of the ferrule. The end 12 is overlapped on the end 14 and the parts 95 are welded together as hereinbefore described.

The device shown in Figs. 5 and 6 is desirable especially when a light gauge metal is used, and by providing the bosses 15, a more secure and positive weld is brought about than is possible otherwise. 100

Having thus described the invention, what is claimed is:

A ferrule for paint brushes, having inner and outer overlapped ends, the outer of said ends 105 being plain, the inner of said ends having outwardly projecting bosses engaging the inner surface of the outer of said ends, the said ends being spot-welded together at the bosses.

VINCENT J. KERSTING. 110
